CENTRIFUGAL PUMP

Alfred C. Korte and Kenneth Lannert, St. Louis,
Mo., assignors to Carter Carburetor Corpora-
tion, St. Louis, Mo., a corporation of Delaware

Application November 5, 1940, Serial No. 364,348

4 Claims. (Cl. 103—87)

This invention relates to fuel pumps and more particularly to electrically driven centrifugal type pumps.

It is an object of the present invention to provide an improved pump of the above character adapted to operate submerged in the liquid to be pumped.

It is a further object of the present invention to provide a novel inexpensive rotor structure for a pump of the above character.

Other objects and advantages will become apparent upon reference to the following description and accompanying drawing.

Fig. 1 is a vertical section of the pump constructed in accordance with our invention.

Fig. 2 is a bottom plan view of the rotor removed.

Numerals 1 and 2 indicate upper and lower sections of the pump housing structure. These sections are provided with flanges 1a and 2a and are attached in any suitable manner as with screws (not shown). Fitted into the upper end of the lower section 2 is a pump casing comprising a disk-like member 3 having a volute groove 4 formed therein and a disk-like cover member 5.

Journalled in the housing structure at 6 and 7 is a vertical rotor generally indicated at 8 which comprises a shaft 9, a motor armature 10, a pump impeller 11, and a commutator 12. The impeller 11 is formed as an integral part of a suitably shaped mass of molded, dielectric material which extends around the armature through the interstices of the winding and downwardly into the shell-like commutator effectively bonding these parts together and to the shaft 9. The general shape of this mass may be varied as desired, in the present form, however, it has been shaped to provide ample protection for the armature and to present a smooth outer surface which will rotate submerged in a liquid with a minimum amount of resistance. It will be also understood that the impeller may be located at either end of the shaft if so desired instead of between the armature and impeller as in the present form. It is to be further understood that any of the commercial synthetic resins or any other non-conducting material having suitable physical properties and which may be molded in a liquid or plastic state may be used to form this mass.

With the above construction it will be apparent that applicants have provided a compact, rigid electric pump rotor having a motor armature, a commutator, an impeller, and a shaft firmly bonded together.

In the present form, the impeller is provided with blades 13 as shown in Fig. 2 which are also formed as an integral part of the insulating mass. Motor field structure is indicated at 14

which is fitted into the upper housing section 1. Pump casing members 4 and 5 are provided with central openings 15 and 16, respectively, through which passes the rotor 8. Opening 15 also provides a central fuel intake to the volute member 4. Circumferentially spaced fuel inlet ports 17 through the wall of lower housing section 2 are provided and a circular screen 18 guards these inlets. Motor brush structure is generally indicated at 19 being supported in the lower housing section 2. A pump discharge passage is indicated at 20 which communicates with the groove 4.

In operation, fuel enters the inlet ports 17 and flows into the spaces between the impeller blades as indicated by the arrows from whence it is thrown by centrifugal force into the volute groove 4 and thence out through the discharge passage 20.

The foregoing description and accompanying drawing are intended to be illustrative and not limiting and the use of all modifications within the scope of the appended claims is contemplated.

We claim:

- 25 1. In a centrifugal pump, a rotor comprising a shaft, an armature core, windings about said core, and a continuous cementitious dielectric mass surrounding said windings and securely bonding together the core, shaft and windings and having an integral portion thereof projecting laterally of said shaft to form a disc-shaped impeller.
- 30 2. In a centrifugal pump, a rotor including a shaft, an armature core and windings about said core, and a continuous cementitious dielectric mass surrounding said windings and bonding said parts as a unit upon said shaft, said mass including a projecting portion constructed and arranged to form an impeller.
- 35 3. In a centrifugal pump, a rotor including a shaft, an armature core and windings about said core, and a continuous cementitious dielectric mass surrounding said windings and bonding said parts as a unit upon said shaft, said mass extending laterally of said shaft in disc-like form at a point spaced from said core to provide an impeller element.
- 40 4. In a centrifugal pump, a rotor including a shaft, an armature core and windings about said core, and a continuous cementitious dielectric mass surrounding said windings and bonding said parts as a unit upon said shaft, said mass extending laterally of said shaft in disc-like form at a point spaced from said core to provide an impeller element, and being reduced in diameter to enclose insulated leads outward of said impeller.
